APPARATUS FOR ORIENTING AND ACCUMULATING ELONGATED ARTICLES

Robert Clark, Parma, and Henry R. Patterson, Shaker Heights, Ohio, assignors to The American Steel and Wire Company of New Jersey, a corporation of New Jersey

Application July 15, 1944, Serial No. 545,176

8 Claims. (Cl. 10—163)

The present invention relates to improvements in apparatus for orienting and accumulating elongated articles in orderly parallel relation as they are successively ejected from the machine which produces them.

While not limited thereto, the invention is peculiarly well suited for the accumulation of foundry pins, which are in the nature of short straight lengths of steel wire pointed on both ends. The users of foundry pins require that they be packed in parallel relation to one another so as to facilitate their later removal from shipping boxes and their ultimate handling by foundrymen. Heretofore it has been the custom to pack such double-pointed foundry pins in cardboard boxes by hand, but such initial packaging has been a slow, laborious and hazardous occupation, since the pins have been ejected in random fashion from the machine which points their ends. Such pins have heretofore merely fallen at random from the machine producing them into a pan, and the points have thus extended haphazardly in all directions. The removal of such double-pointed pins from the pans by hand and the arranging of them in parallel relation prior to shipment in boxes has therefore been a slow and hazardous process in which the fingers of operators have been frequently cut and pricked.

The present invention provides improved means for orienting each pin as it is ejected from the machine for pointing them, and for guiding the pins to a container and agitating them therein so as to insure that each batch of the accumulated pins is maintained in horizontal position and parallel to the other batches. Thus the accumulated pins can be removed from the container in orderly parallel batches and can be easily, safely and quickly placed in small cardboard or other suitable boxes for shipment to the customer.

The invention will be fully apparent from a consideration of the following detailed disclosure, the accompanying drawings, and the appended claims.

In the drawings:

Figure 1 is a general view, partly in elevation and partly in section, showing somewhat diagrammatically the elements of a nail machine which is well adapted for severing and pointing pins, the view illustrating the coordination with such nail machine of the pin orienting and accumulating apparatus embodying the herein claimed invention.

Figure 2 is a section on the staggered line II—II of Figure 1.

Figure 3 is a vertical section on line III—III of Figure 1.

5 Figure 4 is a side elevation of the parts shown in Figure 3.

Figure 5 is a perspective detail view showing the chief component parts of the mechanism for engaging and disengaging the split nut from the 10 lead screw which propels the container-supporting carriage.

Referring in detail to the drawings, 10 represents a frame member of a conventional form of nail making machine provided with any conventional form of wire feeding grippers 12 actuated by suitable cam-operated means in a manner well known to those skilled in the art and therefore not further illustrated herein. The nail machine is equipped with conventional pinch dies 14 which hold the wire or rod-like stock S. As each predetermined increment of stock is longitudinally advanced, pointing dies 16—16 are moved by suitable cam-actuating mechanism by conventional means, so as to sever the 20 stock simultaneously and point the pins in a manner well known to those skilled in the art and therefore not further illustrated. As each increment of advanced wire or rod stock is severed and pointed, the resulting article, which in the 25 case illustrated is a foundry pin, falls endwise and drops in a substantially vertical direction into a guide member 18 whose upright walls 20 converge downwardly. The upper dimension of the guide 18, as viewed in Figure 1, is approximately equal 30 to the greatest length of foundry pin or other elongated article ejected by the nail-making type of processing machine illustrated. As the stock is severed, the article drops endwise, as shown in dotted lines a—a in Figure 1. A top guard 35 22 is provided to prevent the accidental upward throwout of pins in the event that the point-cutting dies 16 fail to function properly, the guard being secured to a top cross member 24 forming part of the pointing or nail making machine. The guide 18 has a suspension member 40 26 secured to its upper end, the upper portion of which is bent at a right angle and secured to the member 24 by a bolt 28.

The lower extremity 30 of the guide 18 telescopically engages the upper portion of an articulate guide chute 32 which is of quadrant-like form, as viewed in Figure 3. This chute is effective to orient the vertically endwise traveling pins from a substantially vertical path of travel to a 45 substantially horizontal path, as is apparent from 50 55

the positions of the pins indicated at *a* in Figure 3. As the thus-oriented pins *a* leave the lower extremity 34 of the chute 32, they enter a substantially horizontal funnel-like member 36 which has secured thereto a bracket 38 fastened to any fixed support. An elongated outlet orifice 40 is formed near one end of the funnel-like member 36 so that as the pins traveling therethrough reach the end thereof they fall through said outlet orifice in a substantially horizontal position.

The outlet end of the funnel-like member 36 projects into the restricted throat portion 42 of a collecting boot indicated as a whole at 44, which is supported by bracket members 46 carried by fixed frame members 48 in turn supported by uprights 50 secured to the base plate 52. Located within the throat portion 42 of the collecting boot is a fixed baffle 54 whose lower end is curved as indicated at 56 and terminates at 58 a short distance from the inner face 60 of an oscillating member 62 which is pivotally mounted on a pin 64. The upper end of the oscillating member 62 has a bent extension 66 perforated to receive a downwardly-projecting finger 68 formed on the end of a pitman rod 70 connected to a crankpin 72 secured to a disc 74 carried by a shaft 76. The shaft 76 carries a sprocket 78 which is connected by a chain 80 with a sprocket 82 carried by the main drive shaft 84 of the pin pointing machine. This shaft 84 carries tight and loose pulleys 86 and 88 and a flywheel 90, and drives suitable conventional means known to those skilled in the art, for actuating the feeding grippers 12, pinch dies 14, and the pointing dies 16.

The lower portion of the collecting boot 44 projects into an elongated box-like container or tote box 92 which is adapted to accumulate the oriented pins and maintain them in horizontal orderly condition parallel to one another. Improved means are provided for automatically moving the tote box or container 92 as the pins gradually accumulate therein and to keep the mass of pins in the upper region of the container gently agitated so as to straighten out any of the pins which tend to move out of parallelism, the lading portion of the container being maintained substantially filled with pins and the container being fed constantly away from the fixed collecting boot. To these ends the container or tote box 92 is supported on a carriage 94 slideable on guides 96 carried by frame members 48. Secured to the carriage is a depending plate 98 having guide slots 100 therein (shown best in Figure 5) for coaction with actuating pins 102 carried by split nut members 104 threaded at 106 for coaction with a feed screw 108. The pins 102 of the split nut pass through cam slots 110 formed in a feed control disc 112 having an actuating handle 114 secured thereto. The feed screw passes freely through openings 116 and 118 respectively, formed in the disc 112 and plate 98. As thus arranged, when the disc 112 is turned in one direction, the split nut members 104 will be operatively engaged with the feed screw 108, and when turned in the opposite direction they will be disengaged from the screw. Such engagement and disengagement is desirable to permit the operator to readily retract the carriage after the container has become fully loaded, and to facilitate the mounting of a new empty container thereon and permit positioning the carriage and the empty container in such a way that the fixed rear upright wall 120 of the container is spaced closely adjacent the upright edge 122 of the boot 44. The forward wall 124 of the container constitutes a gate which is pivotally

mounted on a pintle 126, and said gate is held releasably in closed position by latch dogs 128 pivoted at 130 and pulled downwardly by springs 132, the dogs engaging latch members 134 secured to the upper portion of the gate.

As shown in Figure 4, under normal operating conditions the pins ejected from the dies of the nail making type of pointing machine substantially fill the space between the oscillating member 62 and the baffle member 54, and similar pins also fill the lower portion of the boot and the lading portion of the container to a level near the top edge of the latter. It is important, when changing containers, to maintain the boot substantially filled. To this end we provide a temporary keeper 136 which is adapted to be inserted downwardly through registering slots 138 and 140. After such engagement, a similar keeper plate 142 will be inserted through a slot 144 formed in the bottom wall of the container 92, so as to prevent the pins from gravitating out of parallelism with one another. While the pins are being accumulated in the container 92, the pivoted end gate 124 is in its substantially horizontal position. In this position its free end engages the plate 98 secured to the supporting carriage.

The feed screw 108 is reduced in diameter at one extremity, as indicated at 146, so as to have freedom for rotation and longitudinal movement in a bearing 148 secured to a bracket 150 carried by the base plate 52. At its opposite end the feed screw is connected by a shaft-coupling 152 with a stub shaft 154 having a worm wheel 156 secured thereto which meshes with a worm 158 forming part of a speed reduction unit indicated as a whole at 160. This speed reduction unit is slideable in guides 162 and is adapted to be adjusted by manipulation of a handwheel 164 secured to an adjusting screw 166 threaded through an upright standard 168 and having a swivel connection with a bracket 170 secured to the reduction unit. The supporting shaft 172 for the worm 158 carries a V-grooved pulley 174 which is driven by a V-belt 176 from a V-grooved pulley formed of two complementary coacting parts 178 and 180, constituting a variable speed drive, the part 180 being spring-loaded and adapted to be manually adjusted toward the part 178 so as to vary the effective driving diameter of the pulley and permit of precision adjustment of the driving speed to suit the rate at which the pins are accumulated in the container. The complementary parts 178 and 180 of the adjustable pulley are mounted on the shaft 76 carried by suitable bearings 184, the part 178 being fixed to the shaft 76 and the part 180 being rotatable with the shaft but splined thereto to permit adjustment toward and from the part 178. The shaft 76, as above described, carries the sprocket 78 which is connected by a chain 80 with the sprocket 82 secured to the shaft 84.

In the normal operation of the mechanism shown and described, it is apparent that a pin pointing machine closely resembling a conventional type nail making machine intermittently advances short increments of wire or rod-like stock. Periodically the pinch dies 14 grip each advanced increment, whereupon the pointing dies 16 come into play and simultaneously sever and point the trailing end of a previously advanced increment and leading end of the oncoming increment. Upon completion of the severing and pointing operation, each double-pointed pin, indicated at *a*, falls in rapid succession into the upper end of the guide 18 whose walls 20-20 con-

verge downwardly so as to compel the pins to travel endwise in a generally vertical downward direction. From the lower extremity of the guide 18 the pins successively enter the arcuate chute 32 which orients them from a generally vertical direction to a substantially horizontal direction. From the orienting chute 32 the pins enter the substantially horizontal funnel-like member 36 and drop through the outlet orifice 40 thereof into the space between the baffle 56 and the oscillating member 42 located in the restricted throat portion 42 of the collecting boot 44. In starting the collecting and orienting operation, the keeper plate 136 is inserted through the registering openings 138 and 140 of the boot, so that a mass of nails is initially collected, approximately filling the boot to the top level, as indicated in Figure 4. The container 92 is initially positioned so that the upright outer wall end 120 thereof is in close proximity to the rear edge 122 of the boot, whereupon the keeper plate 136 is withdrawn. Immediately thereafter the mass of oriented substantially parallel horizontal pins in the boot moves down the inclined or arc-shaped bottom wall thereof and into contact with the upright wall 120 of the container.

While the machine is in operation, the oscillating member 62 agitates the mass of pins in the upper regions of the collecting boot and the container. The feed screw, through the driving mechanism described, slowly and gradually feeds the carriage so as to move the rear wall 120 of the container away from the boot at a rate commensurate with that at which the pins are discharged by the pointing machine. In this way a large batch of pins is collected in an orderly and methodical manner, without danger of their being moved out of parallelism with one another. The transverse width of the box-like or hollow prismatic container is slightly greater than the length of the double-pointed pins. The container is of considerable length, being of a size adapted to accumulate, for example, a single batch of fifty or sixty pounds of pins. Upon the accumulation of such a batch, the operator inserts the keeper bar 136 in the boot so as to retain the same substantially filled, and inserts another plate 142 down through the mass of nails and engages it with the slot 144 in the bottom of the container so as to prevent them from falling out endwise when the container is lifted off the carriage 94. After the container has been lifted from the carriage, the end gate 124 is swung to the vertical position of Figure 1, in which position it is held by the latch dogs 128 engaging the bars 134. The plate 142 may then be removed slowly, permitting the pins to gravitate until they contact the closed end gate 124. The container will then be transported to a packaging department, whereupon the pins can be lifted out in small batches by hand or the end closure gate 124 can be swung downwardly and the container tilted so as to permit the parallel pins to flow by gravity into a suitable cardboard or other container. Thus the double-pointed pins can be quickly, easily, and safely packed for shipping in an orderly, parallel horizontal position, which is the position in which the users of foundry pins usually specify that they be made available. While the described mechanism is peculiarly well suited for the orienting and accumulating of double-pointed pins, it will be understood that it is also well suited for accumulating and orienting various elongated

straight pin- or nail-like articles with or without heads or points on one or both ends.

While we have described with great particularity an embodiment of the invention which an actual reduction to practice has demonstrated to be highly advantageous, it is to be understood that various modifications and substitutions of equivalents may be made by those skilled in the art without departure from the invention as defined in the appended claims.

We claim:

1. Apparatus for orienting and accumulating elongated articles as they are ejected from a machine which has acted upon them, comprising an upright guide into which the articles are ejected and along which they are adapted to travel endwise in an approximately vertical direction, orienting means for changing the travel of the articles to a substantially horizontal direction, a member for receiving articles from the latter and having a substantially horizontal elongated outlet in the bottom thereof, an article-accumulating boot having a throat portion below said outlet and adapted to receive articles as they fall by gravity therethrough, a container into which said boot projects, means for agitating the articles in the throat portion of said boot and in the upper regions of said boot and container, and means for movably supporting the container.
2. Apparatus for orienting and accumulating elongated articles as they are ejected from a machine which has acted upon them, comprising an upright guide into which the articles are ejected and along which they are adapted to travel endwise in an approximately vertical direction, orienting means for changing the travel of the articles to a substantially horizontal direction, a member for receiving articles from the latter and having a substantially horizontal elongated outlet in the bottom thereof, an article accumulating boot having a throat portion below said outlet and adapted to receive articles as they fall by gravity therethrough, a container into which said boot projects, means for agitating the articles in the throat portion of said boot and in the upper regions of said boot and container, a carriage for supporting the container, and means for gradually moving it and the container away from the boot as the articles accumulate in the container.
3. Apparatus for orienting and accumulating elongated double-pointed pins as they are ejected from a machine for pointing the ends thereof, comprising a downwardly-converging guide into which the pins are ejected and along which they are adapted to successively travel endwise in an approximately vertical direction, a curved chute for changing the endwise travel of the pins to a substantially horizontal direction, a member receiving pins from said chute and having a substantially horizontal elongated outlet in the bottom thereof through which the pins are adapted to successively drop by gravity, a pin-accumulating boot having a throat portion below said outlet and adapted to receive the pins as they fall therethrough, a container into which the boot projects, an oscillating member and a baffle plate coacting therewith located in said throat portion past which each pin falls by gravity while en route to said container, a movable support for the container, and means for gradually feeding the support and the container away from the boot as the pins are accumulated in parallel horizontal relation to one another in the container.

4. Apparatus for orienting and accumulating elongated articles as they are ejected from a machine which has acted upon them, comprising an upright downwardly-tapering guide into which the articles are ejected and along which they are adapted to fall endwise in an approximately vertical direction, an arcuate quadrant-like chute connecting with the lower end of said guide and adapted to receive articles therefrom in substantially vertical position and discharge them in substantially horizontal position, a funnel-like member adjacent the discharge end of said arcuate chute and having a substantially horizontal outlet in its under side, a fixed collecting boot having a restricted throat portion positioned to receive articles falling from said member through said outlet, a container into which said boot projects, and means for agitating the articles in said throat portion of said boot and the upper region of said container so as to maintain the articles substantially in horizontal parallel relation to one another as they are accumulated in said container.

5. Apparatus for orienting and accumulating elongated articles as they are ejected from a machine which has acted upon them, comprising a container, means for gradually feeding the latter in a substantially horizontal plane, a normally fixed collecting boot having an inclined bottom portion projecting into said container, said boot having a restricted inlet throat portion, an upright movable member and an upright fixed plate whose lower extremity converges toward said member, and means for oscillating said member so as to agitate the articles in the throat portion of said boot and in the upper regions of said boot and container and thus insure that the successively fed articles accumulated in said container are maintained in substantially parallel horizontal relation to one another.

6. In combination with means for intermittently delivering pin-like articles in succession in horizontal position, an apparatus for accumulating said articles, comprising an upright guide into which the articles are ejected and along which they are adapted to travel endwise in an approximately vertical direction, means for changing the travel of the articles to a substantially horizontal direction, a member for receiving articles from

the latter and having a substantially horizontal elongated outlet in the bottom thereof, an article-accumulating boot having a throat portion below said outlet and adapted to receive articles as they fall by gravity therethrough, a container into which said boot projects, means for agitating the articles in the throat portion of said boot and in the upper regions of the boot and container, and means for movably supporting the container.

7. The combination with means for delivering elongated articles in succession in horizontal position, of a collecting member having a restricted throat portion to receive said articles, means for agitating the articles contained in said throat portion, a horizontally-disposed box-like container into which said collecting member extends, the bottom wall of said member being inclined and terminating substantially at the plane of the inner face of the bottom horizontal wall of the container, means for gradually feeding the container away from the collecting member, and means for varying the rate of feed of said feeding means so as to coordinate the feed with precision to the rate at which articles are accumulated in the container, whereby the lading portion of the container between the collecting member and the upright end wall remote from said member is kept substantially filled to capacity with articles disposed in horizontal parallel relation to one another.

8. The combination with means for delivering elongated articles in succession in substantially horizontal position, of a collecting member having a restricted throat portion to receive said articles, means for agitating the articles contained in said throat portion, a horizontally-disposed box-like container into which said collecting member extends, the bottom wall of said collecting member being inclined and terminating substantially at the plane of the inner face of the horizontal bottom wall of the container, a carriage on which the container is mounted, mechanism for feeding the carriage gradually away from said collecting members including a speed reduction unit, and variable speed driving means transmitting motion to said reduction unit.

ROBERT CLARK.
